CLAIM

The ornamental design for a display panel with a transitional temperature control graphical user interface, as shown and described.

DESCRIPTION

FIG. 1 is a perspective view of the display panel with a transitional temperature control graphical user interface showing our new design;

FIG. 2 is a front perspective view of the display panel with a transitional temperature control graphical user interface of FIG. 1;

FIG. 3 is a front view of the display panel with a transitional temperature control graphical user interface of FIG. 1 wherein an enlarged view of the graphical user interface illustrated is shown separately for completeness of illustration, and showing a first image of the claimed design; and, FIG. 4 is a front view of the display panel with a transitional temperature control graphical user interface of FIG. 1 wherein an enlarged view of the graphical user interface illustrated is shown separately for completeness of illustration, and showing a second image thereof which has transitioned from the first image of FIG. 3.

In FIGS. 1-2, broken lines illustrate environmental structure that form no part of the claimed design. In FIGS. 3-4, broken lines indicate portions of the graphical user interface that form no part of the claimed design.

The appearance of the transitional image sequentially transitions between the images shown in FIGS. 3-4. The process or period in which one image transitions to another image forms no part of the claimed design.
